UNITED STATES PATENT OFFICE.

JOHN PFAFF, OF PHILADELPHIA, PENNSYLVANIA.

IMPROVEMENT IN TAIL-PIECES FOR VIOLINS.

Specification forming part of Letters Patent No. 35,256, dated May 13, 1862.

To all whom it may concern:

Be it known that I, JOHN PFAFF, of Philadelphia, Pennsylvania, have invented a new and useful Improvement in Tail-Pieces for Violins; and I do hereby declare the following to be a full, clear, and exact description of the same, reference being had to the accompanying drawings, and to the letters of reference marked thereon.

My invention relates to an improvement in the tail-piece for violins, for which Letters Patent were granted to me on the 7th day of June, 1859; and my improvement consists in combining with a tail-piece a tongue, of thin metal, so arranged and of such dimensions that by applying the mouth to the stem of the tail-piece and blowing against the tongue the vibration of the latter will give out a note for guiding the performer in tuning his instrument.

In order to enable others to make and use my invention, I will now proceed to describe its construction and operation.

On reference to the accompanying drawings, which form a part of this specification, Figure 1 is a plan view of my improved tail-piece for violins, and Fig. 2 a longitudinal section.

A represents the tail-piece, which is made of any metal or alloy of metal capable of being readily bent without breaking, one end of the tail-piece being bent down, as shown by red lines, Fig. 2, and terminating in an eye, a, for fitting over a peg attached to the end of the body of the violin, as usual. The oppo-

site end of the tail-piece has two arms, e e, connected together by the cross-bar f, this end being otherwise constructed in the manner described in my aforesaid patent for the reception of the knotted ends of the strings.

In the stem of the tail-piece an oblong opening is formed at the point x, and above this opening is a tongue, y, of thin metal, riveted or otherwise secured at one end to the tail-piece, the tongue being of such dimensions that while it nearly coincides with the oblong opening it is free to vibrate freely without coming in contact with the sides or end of the said opening. The tongue is, in fact, arranged on the tail-piece precisely as the tongues or reeds of accordions, melodeons, or other like instruments are on the slotted plates to which they are attached. The tongue is of course so constructed and of such a size that when the mouth is applied to the tail-piece, and the tongue blown against such, a note will be given out as will guide the performer in tuning his instrument.

I claim as my invention and desire to secure by Letters Patent—

Combining the tongue y with the tail-piece of a violin, substantially as and for the purpose herein set forth.

In testimony whereof I have signed my name to this specification in the presence of two subscribing witnesses.

JOHN PFAFF.
